UNITED STATES PATENT OFFICE.

WILLIAM D. MANN, OF NEW YORK, N. Y., ASSIGNOR TO MANN'S BOUDOIR CAR COMPANY, OF SAME PLACE.

PANEL FOR USE IN THE CONSTRUCTION OF CARS, BOATS, &c.

SPECIFICATION forming part of Letters Patent No. 311,022, dated January 20, 1885.

Application filed June 21, 1884. (No model.)

To all whom it may concern:

Be it known that I, WILLIAM D'ALTON MANN, a citizen of the United States, and a resident of New York, in the county and State of New York, have invented a certain new and useful Improvement in the Construction of State-Rooms for Railway-Cars, Steamboats, &c., of which the following is a specification.

The invention has for its object the provision of sliding panels of such construction that the binding thereof, caused by the warping of the parts, is effectually prevented, while at the same time, when closed, the air may have free circulation around the same and through the state-room and vision be completely cut off.

In order that the invention may be fully understood, I will proceed to describe it with reference to the accompanying drawings, in which—

Figure I is a perspective view of one of the improved sliding panels removed. Fig. II is an elevation of the same in position in the frame. Fig. III is a horizontal section thereof.

The invention is specially adapted for use in the construction of sleeping-cars—such as described in my contemporaneous application filed on the 25th of March, 1884, Serial No. 125,451—but is applicable to any structures where found desirable.

I may represent the wall or partition which separates the state-room from some other apartment of a structure, being provided with grooves or channels 2, which confine the panels 3 and permit their free vertical movement, as hereinafter explained. The panels 3 are constructed with tongues 4, which are short vertically, and project horizontally from

the upper and lower corners thereof, and enter the vertical grooves 2 in the partition 1. 40 By the use of these short tongues 4 the panels are effectually confined, while being adapted to slide freely up and down without the danger of cramping or binding, which is liable to occur from the warping of the parts, caused 45 by changes of temperature, or from straining or unequal settling of the jamb when the edges of the panels engage throughout their length in the guiding-grooves. The edges of the panels between the tongues 4 are beveled, as 50 shown at 5, the beveled portions projecting within the guiding-grooves 2 without contact, so as to completely exclude vision, while at the same time permitting the free circulation of air around the same and precluding the 55 liability of the panel to stick or jam. These sliding panels may be provided with lifts and locks of any suitable form on the inside, enabling the occupant of the room to move or tightly secure the panels at pleasure. 60

Having thus described my invention, the following is what I claim as new therein and desire to secure by Letters Patent:

The sliding panels, substantially as herein-before described, constructed with guiding-tongues for a small portion of their length, and with a thin or beveled edge for the remainder thereof, in combination with a frame or jamb having guiding-grooves, into which said tongues and edges project, as and for the 65 purpose explained. 70

W. D. MANN.
